[57] CLAIM

The ornamental design for a body for a toy figure, as shown and described.

DESCRIPTION

FIG. 1 is a front right side perspective view of a body for a toy figure showing my new design;

FIG. 2 is a top plan view thereof;

FIG. 3 is a right side elevational view, left side being substantially a mirror image thereof;

FIG. 4 is a front elevational view thereof;

FIG. 5 is a rear elevational view thereof; and,

FIG. 6 is a bottom plan view.

The broken line showing of a toy head is to show environment only.

FIG. 2

FIG. 1

FIG. 3

FIG. 4

FIG. 5

FIG. 6
